HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,365,323.

Specification of Letters Patent. Patented Jan. 11, 1921.

Application filed May 12, 1919. Serial No. 296,491.

To all whom it may concern:

Be it known that I, HENRY D. JAMES, a citizen of the United States, and a resident of Edgewood Park, in the county of Allegheny and State of Pennsylvania, have invented a new and useful Improvement in Control Systems, of which the following is a specification.

My invention relates to motor-control systems and particularly to systems for controlling the excitation, during acceleration, of the shunt field-magnet windings of direct-current motors.

The object of my invention is to provide an improved control system of the above-designated character.

In a system arranged according to my invention, the resistor that is in circuit with the shunt field-magnet winding is controlled by a normally open switch that is provided with a coil connected across the armature resistor. Upon the current falling to a predetermined value, or upon the armature resistor becoming short-circuited, the coil becomes sufficiently deenergized to permit the opening of the switch, whereby the field resistor is inserted into circuit.

In the accompanying drawings, Figures 1 and 2 are diagrammatic views of control systems embodying my invention.

A direct current motor, having an armature 1 and a shunt field-magnet winding 2, is connected between line conductors 3 and 4 by a line contactor 5, with an accelerating resistor 6 in series with the armature 1. The contactor 5 is adapted to be closed, upon a master switch 7 being moved to its first position, to establish the circuit of an actuating coil 8, which circuit comprises contact members 9 and 9^a. A plurality of contactors 10, 11 and 12 are adapted to effect the short-circuiting of resistor portions 13, 14 and 15, respectively, of the resistor 6, upon the master switch 7 being successively actuated to positions in which it engages contact members 16, 17 and 18, respectively. The contactors 10, 11 and 12 are respectively provided with actuating coils 19, 20 and 21, the circuits of which are respectively controlled by the contact members 16, 17 and 18. I have shown the contactors 5, 10, 11 and 12 as controlled by a master switch 7 of the drum type, but it will be understood that a controller of any other type may be substi-

tuted therefor and that these contactors may be replaced by switches operated, for example, by a cam controller.

In Fig. 1, a resistor 22 is provided in circuit with the shunt field-magnet winding 2, the effective portion of which may be adjusted as desired and the remaining portion of which is under the control of a relay 23, having an actuating coil 24 that is connected across portions of the resistor 6, as, for example, the portions 14 and 15. In Fig. 2, the resistor 22 is adapted to be controlled in two steps by relays 23 and 25 having actuating coils 24 and 26, respectively, which are connected across portions of the resistor 6 as, for example, the portions 13 and 14, and 14 and 15, respectively. It will be understood that the particular connecting points of the coils 24 and 26 which are here shown are shown for purposes of illustration only and that it is within the scope of my invention to connect these coils in relation other than that above described.

The operation of the system of Fig. 1 may be described as follows: Upon the actuation of the master switch 7 to its first position, wherein it engages contact members 9 and 9^a, a circuit is established from the line conductor 3, through the contact members 9^a and 9, which are bridged by the master switch 7, and the coil 8, to the line conductor 4. The contactor 5 is thereupon closed by its actuating coil 8 to close the motor circuit. Current then flows from the line conductor 3, through the armature 1 and the resistor 6 on the one hand and the shunt field-magnet winding 2 and the resistor 22 on the other, in parallel, and the contactor 5, to the line conductor 4. The coil 24 becomes thereupon energized by the voltage drop across that portion of the resistor to which it is connected, effecting the closing of the relay 23 and the short-circuiting of the resistor 22. The motor may be then accelerated, with the field-magnet winding 2 strongly excited.

Further actuation of the master switch 7 to its successive positions will result in the successive closing of the circuits of the coils 19, 20 and 21, which, in turn, effect the successive closing of the contactors 10, 11 and 12 to short-circuit the resistor portions 13, 14 and 15. Upon the resistor portions 14 and 15 becoming short-circuited, the coil 24 be-

comes subjected to the voltage drop of a portion 16 of the resistor 6 which, when the motor speed attains a predetermined value, is so small that the coil 24, energized in accordance therewith, is not able to maintain the relay 23 closed. The relay 23 is therefore opened by force of gravity to effect the reinserting into the circuit of the field-magnet winding 2 of the resistor 22, whereupon the motor accelerates to its maximum speed.

The system of Fig. 2 is similar to that of Fig. 1, the coil 24 becoming deenergized upon the short-circuiting of the resistor portions 13 and 14, whereupon a portion only 15 of the resistor 22 is inserted into the circuit of the field-magnet winding 2. When the resistor portion 15 is also short-circuited, the coil 26 is unable to maintain the relay 26 closed, whereupon the remaining portion of 20 the resistor 22 is inserted into the circuit of the field-magnet winding 2.

In this system, the relays 23 and 25 may open alternately with the closing of some of the contactors 10, 11 and 12. Thus, in the 25 system as illustrated, the relay 23 is opened following the closing of the contactor 11 and before the closing of the contactor 12. The system may be so designed, however, that the relay 23 opens following the closing 30 of the contactor 10. Thus, the resistor portion 14 may be so designed that, after the motor has attained a certain predetermined speed, the voltage drop across the resistor 14 will be sufficient to energize the coil 24 35 strongly enough to maintain the relay 23 closed.

Although I have shown two systems embodying my invention, it will be understood that the invention is not restricted thereto, 40 but that other and equivalent systems may be devised falling within the spirit and scope of the invention, as expressed in the appended claims.

I claim as my invention:

1. The combination with an electric motor 45 having armature and field-magnet windings and resistors in circuit therewith, of means controlled in accordance with the drop in potential across one of said resistors for controlling the other of said resistors.

2. The combination with an electric motor having armature and shunt field-magnet windings and resistors in circuit therewith, of means controlled in accordance with the drop in potential across said armature resistor 50 for controlling said field-magnet resistor.

3. The combination with an electric motor having armature and shunt field-magnet windings and resistors in circuit therewith, 55 of a switch for controlling said field-magnet resistor having a controlling coil connected across said armature resistor.

4. The combination with an electric motor having armature and shunt field-magnet 65 windings, resistors in circuit therewith, a switch for short-circuiting said armature resistor, and means for actuating said switch, of a switch biased to open position for short-circuiting said armature resistor when closed 70 and having a closing coil connected across said armature resistor that is adapted to permit the closing of said biased switch following the actuation of said actuating means.

5. The combination with an electric motor 75 having armature and shunt field-magnet windings, and resistors in series therewith, of a plurality of switches for controlling said field resistor having actuating coils connected across portions of said armature resistor.

In testimony whereof, I have hereunto subscribed my name this 23d day of April, 1919.

HENRY D. JAMES.
